UNITED STATES PATENT OFFICE.

HUGH R. McLACHLAN, OF PITTSBURGH, PENNSYLVANIA.

INTERLOCKING BONDING BLOCK.

Application filed June 11, 1925. Serial No. 36,390.

This invention relates to building blocks and more in particular to interlocking-bonding-blocks to be used especially in the construction of boiler settings made up of a fire brick wall and an outer brick wall separated by an air space.

The primary object of this invention is to provide an interlocking-bonding-block made of refractory material which is adapted to 10 allow for the expansion or contraction in all directions of the fire brick walls due to the heat generated in the furnace chamber of a boiler. Another object of this invention is to provide an interlocking-bonding-block, 15 which is capable of supporting the heavy loads due to the portions of the fire wall built over it. A further object of this invention is to provide such a bonding-block, the component parts of which may be easily 20 molded and which, therefore, can be manufactured at a relatively low cost. Additional features and advantages of this invention will appear from the following description considered in connection with the accompanying drawing forming a part of this 25 application.

In the drawing:—

Fig. 1 is a side elevation of the so-called male portion of the interlocking-bonding-block.

Fig. 2 is a bottom plan view of Fig. 1.

Fig. 3 is a rear elevation of Fig. 1.

Fig. 4 is a side elevation of the so-called female portion of the interlocking-bonding-block.

Fig. 5 is a top plan view of Fig. 4.

Fig. 6 is a rear elevation of Fig. 4.

Fig. 7 is a front elevation of Fig. 4.

Fig. 8 is a perspective view showing the 40 complete interlocking-bonding-block.

Fig. 9 is a fractional vertical cross-section taken through a boiler setting wall built with interlocking-bonding-blocks forming the subject matter of this invention.

Fig. 10 is a front elevation of the inner wall of the boiler setting.

Reference being had especially to Figs. 1 to 3, the male half of the bonding-block comprises a rectangular body portion 1 the front end 2 of which is straight and of twice the height and twice the width as the standard bricks used in the inner and outer wall of the brick setting. The rear end of said male portion comprises an overhanging member, or ledge, 3 having a down and inwardly directed face 4 and an upwardly di-

rected bottom 5. Centrally disposed below the ledge and level with the bottom 6 of the body portion is the bracket 7 having a straight rear face 8 and a top 9 which suitably declines from the rear inwardly until it strikes the edge 10 formed by the planes 4 and 5.

The female half of the interlocking-bonding-block, shown particularly in Figs. 4 to 7 is composed of the body portion 11, of the same cross-section as the male body, preferably, and having at each side of the top 12 of the front end 13 a rectangular recess 14 of substantially the same length and 70 depth as the standard brick from which the inner wall is built, and having a width equal substantially to one half the width of said standard brick. The central web 15 is, therefore, of the same size as a standard 75 brick. The rear end 16 of the female half has a face 17 which is partly tapered down and outwardly to conform with the taper of the face 4 of the male half and is terminated by the two parallel and spaced fingers 18, the top 19 of which is inclined to fit the taper of the bottom 5 of the male half. The open space 20 between the fingers, and the recess 21 cut in the bottom of the female half and reaching underneath the face 17, are adapted to receive the bracket 7 of the male half.

The engaging portions of the male and female halves of the interlocking-bonding-block are suitably dimensioned to provide 90 sufficient loose-play to allow for the normal amount of expansion or contraction which may occur in the inner and outer walls of the boiler setting. It will be found in practice that a clearance of about one eighth of 95 an inch between the interlocking parts of the two halves will answer the purpose.

Referring to Fig. 8, in which the clearances for loose-play are indicated by the numeral 22, it will be noted that, once the 100 male and female halves of the bonding-block are assembled and the latter is laid in the brick work of the boiler setting, it will be impossible to fully separate said halves and the inward or outward movements of the 105 inner wall, due to the variations in the temperature in the fire chamber, will be limited by the loose-play in the bonding-block. This same loose-play will also amply provide for all vertical or horizontal movements of the 110 walls.

Owing to the particular construction of

the interlocking-bonding-block, the latter is also well suited for supporting its allotted share of the weight of either the inner or outer wall of the boiler setting. In Fig. 9 5 is shown the condition wherein part of the inner wall is assumed to have been completely destroyed by the action of the fire and wherein the lower bonding-block is supporting a detached portion of said wall. This 10 is a very important advantage of said block, as it prevents the crumbling down of the upper, and still usable, portion of the wall, due to the fact that the bonding-block is of the same kind of refractory material as the 15 standard fire bricks, but substantially four times as large in cross-section, hence being capable of resisting the effects of the fire much longer than said standard bricks. Moreover, the interlocking portions of the 20 bonding-block, being situated in the air space 25, are not exposed to the intense heat in the fire-chamber.

To disguise the presence of the heavy bonding-blocks and maintain the uniform 25 appearance of the mortar joints, the visible front ends of the two halves of the bonding-block are preferably provided with suitably placed grooves 23 and 24 which simulate said mortar joints.

30 Where the conditions of the construction or the size of the bonding blocks require it, the male and female halves are reinforced with steel bars imbedded therein to assist the engaging portions of both halves to 35 better sustain the loads and stresses imposed upon them. Thus, the male half is reinforced with the steel rod 26 bent substantially into the shape of a U and the female half is strengthened by the similarly 40 bent steel rod 27 reaching from the body 11 into the fingers 18. Owing to their positions, these reinforcing bars will at all times be protected against the intense heat of the fire.

45 As will be readily understood, any desired width of air space 25 in the boiler setting walls may be obtained by suitably varying the length of the body portions of either one or both halves of the interlocking-bonding-block.

Obviously, the invention is not limited or restricted to any kind of material employed, or restricted to the precise and exact details and proportions of the construction as illustrated and described, nor is its use 55 limited to the construction of boiler setting walls, furnace walls, etc., because it is susceptible of a variety of embodiments and applications, and minor details may be 60 changed in such preferred incorporation of the invention without departing from the spirit and scope of the invention as claimed.

I claim:—

65 1. In a bonding-block of the character described, a male part; a female part, said

male part having a ledge positioned at the rear end thereof and provided with a downwardly beveled face and an upwardly beveled bottom, and a central bracket positioned below said ledge, the top of said 70 bracket starting at the apex formed by the face and bottom of said ledge and tapering upwardly therefrom to its rear end; the female part having at its rear end two spaced fingers in parallel relation and a recessed portion both adapted to receive therebetween said bracket, the rear face and fingers of said female parts being beveled to conform to the shape of said ledge and bracket engaged thereby. 75

2. In a bonding-block of the character described, a male part; a female part, said male part having a ledge positioned at the rear end thereof and provided with a downwardly beveled face and an upwardly beveled bottom, and a central bracket positioned below said ledge, the top of said 80 bracket starting at the apex formed by the face and bottom of said ledge and tapering upwardly therefrom to its rear end; the female part having at its rear end two spaced fingers in parallel relation and a recessed portion both adapted to receive therebetween said bracket, the rear face and fingers of said female part being beveled to 85 conform to the shape of said ledge and bracket engaged thereby; said female part having also two parallel rectangular recesses positioned longitudinally at the top corners of the front end thereof and adapted to 90 support the adjacent bricks of the brick wall in which said female part is incorporated. 95

3. In a bonding-block of the character described, a male part; a female part, said male part having a ledge positioned at the rear end thereof and provided with a downwardly beveled face and an upwardly beveled bottom, and a central bracket positioned below said ledge, the top of said 100 bracket starting at the apex formed by the face and bottom of said ledge and tapering upwardly therefrom to its rear end; the female part having at its rear end two spaced fingers in parallel relation and a recessed portion both adapted to receive therebetween said bracket, the rear face and fingers of said female part being beveled to 105 conform to the shape of said ledge and bracket engaged thereby; said female part having also two parallel rectangular recesses positioned longitudinally at the top corners of the front end thereof and adapted to support the adjacent bricks of the brick wall in which said female part is incorporated. 110

4. In a bonding-block of the character described, a male part; a female part; means 115

120

125

130

- formed integrally with said parts for removably locking them together; said locking means being adapted to afford a predetermined amount of relative displacement of 5 said parts in all directions and to permit the imposition of loads on either one of said parts when unsupported, and reinforcing means imbedded individually in said male and female parts.
- 10 5. In a bonding-block of the character described, a male part; a female part; said male part having a ledge positioned at the rear end thereof and provided with a downwardly beveled face and an upwardly 15 beveled bottom, and a central bracket posi-
- tioned below said ledge, the top of said bracket starting at the apex formed by the face and bottom of said ledge and tapering upwardly therefrom to its rear end; the female part having at its rear end two spaced fingers in parallel relation and a recessed portion both adapted to receive therebetween said bracket, the rear face and fingers of said female part being beveled to conform to the shape of said ledge and 20 bracket engaged thereby; and reinforcing means imbedded individually in said male and female parts.

In testimony whereof I affix my signature.

HUGH R. McLACHLAN.
